GRINDING

Arthur N. Emmons, Nedrow, N. Y.

Application January 12, 1943, Serial No. 472,095

5 Claims. (Cl. 51—135)

This invention has to do in general with grinding, and more particularly with a method of precision grinding employing apparatus of the belt type wherein an endless abrasive belt is operated over a pair of pulleys.

Grinding operations have heretofore been carried out by holding the work against an abrasive belt. If the belt were not backed up by a platen, the operation was more of a buffing or polishing operation to produce a smooth surface to enhance the appearance of the object being operated upon. The prior method also included such an operation with the belt backed by a platen and in that instance, the operation was performed to produce an approximate flat surface. With this method, the surface operated upon was only approximately flat or uniform due to the fact that even though the surface of the platen over which the belt was run was flat with close limits, the abrasive belt has a tendency to move relative to the platen, or portions of the belt do not follow the contour of the platen due to curling, uneven tension through the width of the belt, etc. Accordingly, this method of grinding was only employed for quickly surfacing parts that did not have to be flat within accurate or close limits.

This invention has as an object a method of grinding with an abrasive belt whereby the parts operated upon are finished with a flat surface equivalent to the accuracy of the platen, and the invention further includes a form of apparatus by which the method can be carried out.

The invention consists in the novel features and in the combinations and constructions hereinafter set forth and claimed.

In describing this invention, reference is had to the accompanying drawings in which like characters designate corresponding parts in all the views.

Figure 1 is a side elevational view of the machine embodying my invention.

Figure 2 is a view, similar to Figure 1, showing the opposite side of the machine.

Figure 3 is a front elevational view of the upper portion of the machine with parts broken away, and parts shown in section.

Figure 4 is a front elevational view of the lower portion of the machine with parts broken away and parts shown in section.

The method consists in holding the work against an endless abrasive belt while running the belt over an accurately surfaced platen, and maintaining the belt in slidable contact with the entire surface of the platen by maintaining a film of liquid between the belt and the platen.

The apparatus herein disclosed consists generally of an enclosed housing in which a pair of pulleys are journaled in spaced apart relationship and over which the abrasive belt is trained. 5 A platen is arranged intermediate the pulleys and preferably adjustable so that it can be positioned slightly forward of a plane tangent with the peripheries of the pulleys. Means is arranged within the housing to maintain a film of liquid, such as water, or a mixture of water and coolant oil between the back of the belt and the surface of the platen. This means may be in the nature of one or more nozzles arranged within the housing and effective to maintain a mist within the housing and adjusted so as to maintain a proper film of the liquid between the belt and platen which I have found causes the belt, probably through surface tension of the liquid, to slidably cling to the surface of the platen, and whereby the accuracy of the surface of the platen is reproduced on the article being worked upon.

For convenience in manufacture and assembling, the frame or housing of the machine is formed in two sections, a lower or base section 10, and an upper section 11 secured thereto by any suitable means as screws, not shown. The forward side of the base section 10 extends outwardly to form a support 12 for a work support 13.

As already explained, the abrasive machine is of the belt type, the abrasive belt 14 being trained over pulleys 15, 16, journaled in the housing.

The pulley 15 is journaled in the lower base section 10, the pulley being fixedly secured to a driving shaft 18 journaled in antifriction bearings 19 carried in a sleeve 20. One side of the base 10 is formed with an inwardly extending boss 21 apertured to receive the sleeve 20, the outer portion of which is formed with a radial flange 22 apertured to receive screws 23 threading into the base section 10 and thereby securing the sleeve 20, with the drive shaft 18 journaled therein, as a unit in the frame of the machine. 45 The outer end of the shaft 20 is provided with a driving pulley 24 which is operatively connected with a similar pulley 25 on a driving motor 26 by means of a belt, or series of belts, 27.

The driving motor 26 is mounted on the rear side of the base section 10. As here shown, the motor 26 is pivotally mounted, as at 30, to a rearwardly extending bracket 31 provided with screws 33, 34, engaging the base of the motor and providing means for adjusting it about the pivot 30 to effect the proper tension upon the driving belt 27.

The upper and lower sections 10, 11, of the housing are of substantially box formation, both open at one side, the opening in the lower section 10 extending to a point below the drive pulley 15, and the opening in the upper section being commensurate therewith. The openings in both sections are closed by a suitable door 37 hinged on the upper section 11. This arrangement permits convenient assembly of the machine and also the convenient changing of the abrasive belts 14.

The upper pulley 16 is journalled for free rotation upon a stub shaft 38 pivoted intermediate its ends at 39 to an inwardly extending portion 40 of a slide 41. The outer end of the stub shaft 38 is pivotally connected, as at 42, to a link 43 vertically adjustable by screw 44 threading into an outwardly extending portion 45 of slide 41.

The adjacent surface of the upper frame section 11 is machined off, and a block 46 is attached thereto as by screws 47. The block 46 is formed with vertically extending dove-tailed ways 48 and the slide 41 is formed with cooperating ways 49. The slide is adjustable vertically relative to the carrying block 46 and the frame of the machine by an adjusting screw 50 having an operating handle 51, the adjacent side wall of the upper section being formed with a concave portion 52 to permit the crank 51 to be operated to permit the slide 41 to be moved upwardly or downwardly by the screw 50 and accordingly, to move the pulley 16 toward and from the bottom pulley 15 to effect proper tension upon the abrasive belt 14.

The purpose of the adjustment effected by the screw 44 is to change the angularity between the axis of the pulley 16 with that of the pulley 15 in order to properly track the belt, these adjustments being well understood by those familiar with the belt type abrasive machine.

In addition to being open on one side, as previously mentioned, the upper section 11 is also open on the forward side to expose a substantial portion of the belt 14. This exposed portion of the belt is backed up by a platen 60 formed with a rearwardly extending web at 61 centrally located, it being formed at each end with elongated apertures 62 to receive screws 63 threaded into bosses 64 extending laterally from one side of the section 11.

With this arrangement, the platen 61 is adjustable toward and from the forward run of the belt 14, and also in angular relation to the work supporting table 13. The platen is maintained in adjusted position by screw 65 threaded through boss 66, with the ends of the screws engaging the ends of the web 61 of the platen. The belt engaging surface of the platen 60 is a true flat plane being preferably hand scraped to a surface plate, or other flat surface, and the platen is adjusted so that the belt engaging surface is somewhat forward of the plane tangent to the periphery of the pulleys 15, 16.

The belt 14 is caused to cling uniformly to the precision surface of the platen and therefore reproduce this precision surface on the work being operated upon by a film of liquid maintained between the belt and the face of the platen by means of one or more nozzles arranged to direct a spray of liquid within the housing of the machine.

As here shown, the nozzle 70 is arranged in the base section 10 and positioned to direct a spray on the face of the abrading belt 14 adjacent the lower pulley 15. A second nozzle 71 is positioned in the upper section 11 and arranged to direct a spray on the face of the belt in proximity to the upper pulley 16. The lower nozzle 70 is fed by a

10 pipe 73 connected to a feed pipe 74 through a valve 75. The upper nozzle 71 is connected to a pipe 76 extending downwardly along one side of the upper section 11 and being connected to the feed pipe 74 through a valve 77, the arrangement being such that nozzles 70, 71 may be used individually, or in unison. The feed pipe 74 is connected to the outlet port of a circulating pump 78 mounted upon a tank 79 and operable to pump liquid therefrom. The pump 78 is operated by a belt 80 trained over a pulley 81 carried by the shaft 18.

The lower section 10 is formed with a transversely extending web 82 of trough formation 15 and one side of the section 10 is provided with an opening 83 connecting with a tank 84. The tank 84 is provided with an aperture 85 arranged in register with the aperture 83, and the tank 84 is connected to tank 79 by connection 87, all 20 whereby the water or coolant cooled in the base section 10 is permitted to drain into the tank 84 wherein any solid material settles to the bottom of the tank and the liquid passes through connection 87 into tank 79 wherefrom it is pumped 25 to the nozzles 70, 71.

The tank 84 is provided with a baffle 88 to assist in the separation of the solid material from the liquid as will be well understood.

The flow of fluid to the nozzles 70, 71, is so adjusted by valves 75, 77, in conjunction with the moving parts of the machine, as to effect a fog or mist within the housing, whereby the back of the belt is moistened to provide a film of liquid between it and the face of the platen. This result can obviously be accomplished by directing a fine spray on the back of the belt. However, I have found that by directing the nozzles 70, 71, on the cutting side of the belt, the back of the belt is properly moistened while an excess of liquid is applied to the face of the belt which aids materially in the free removal of chips from the abrasive on the belt and thereby permitting the belt to be run at much higher speeds upon a given material.

45 This method of grinding has the additional advantage of maintaining the belt at a relatively low temperature while, at the same time, permitting it to be operated under considerable tension over the face of the platen.

With this method, work can be quickly finished to extremely close tolerances without requiring an additional grinding operation on a surface grinder, or other more expensive and slower operating machines.

55 What I claim is:

1. In a method of precision grinding consisting of holding the work against an endless abrasive belt while running the same over a platen having a true flat surface and holding the back of the work engaging portion of the belt in slidable contact against the surface of the platen by maintaining a film of liquid between the belt and the platen.

65 2. In a method of precision grinding consisting of holding the work against an endless abrasive belt while running the belt over a platen having a true flat surface and holding the belt in slidable contact against the entire surface of the platen by maintaining a film of liquid between the belt and the platen.

3. Grinding apparatus comprising a frame, a pair of pulleys journalled in the frame and spaced apart in parallel relationship, an endless abrasive belt trained over said pulleys, a platen carried by the frame and positioned between said pulleys,

said platen having a flat surface positioned forward of the plane tangent to said pulleys and engaging the rear side of the belt, means operable to maintain a film of liquid between said belt and surface of the platen, and means operable to effect rotation of said pulleys.

4. Grinding apparatus comprising an enclosed housing having an opening in one side thereof, a pair of pulleys journaled in the housing in spaced apart parallel relationship, an endless abrasive belt trained over said pulleys with a portion of the belt exposed through said opening, a platen arranged in said opening and detachably secured to the housing, said platen having a flat surface engaging the rear side of the belt and being adjustable toward and from the belt, means operable to maintain a film of liquid between said belt and the surface of the platen, and motive means operable to effect rotation of said pulleys.

5. Grinding apparatus comprising an enclosed housing having an opening in one side thereof, a pair of pulleys journaled in the housing in spaced apart parallel relationship, an abrasive belt trained over said pulleys and having a portion exposed through said opening, a work supporting table carried by the housing and positioned exteriorly thereof in juxtaposition to said opening, a platen detachably mounted in the housing and having a flat surface engaging the rear surface of the exposed portion of said belt, said platen being adjustable toward and from the belt and angularly to said table, a spray nozzle arranged in the housing and being operable to maintain a film of liquid between the belt and the surface of said platen, and motive means operable to effect rotation of said pulleys.

ARTHUR N. EMMONS.
